ELECTRIC MACHINE

George E. Losier, East Orange, N. J., assignor of
one-fifth to William A. Hughes, Newark, N. J.,
and four-fifths to Marion Losier, East Orange,
N. J.

Application April 21, 1933, Serial No. 667,214

1 Claim. (Cl. 178—6.6)

The present invention relates generally to a method and steps, to a machine and to a system of distribution for making mechanical reproductions at a distance from an original image, picture or pattern; and the present invention relates to a method and steps, to a machine and to a system of distribution for transmitting an image, picture or pattern from a sending station by wire or radio to produce a printing plate or other device at a receiving station. The present invention relates further to a method and steps, to a machine and to a system of distribution for transmitting, in a simple and economical manner, a picture to a distant station and producing thereat, by means of the transmitted energy, an engraved plate substantially ready for printing screen effect half-tone pictures.

An object of the present invention is to provide method and means for scanning a picture at one point, for producing a screen effect half-tone printing plate at a distant point by means governed and controlled by the scanning means, and for synchronizing the scanning means and the picture plate producing means.

Another object of the present invention is to provide a method and means for transmitting a picture from a photoelectric scanning means to produce a screen effect half-tone picture plate at an electrically controlled cutting machine, and utilizing the means for producing the screen effect for synchronizing the scanning means and the cutting machine.

Another object of the present invention is to provide a screen effect picture scanning means and a picture plate cutting means controlled thereby, which employ constant speed reciprocating movement between the picture and scanning means and between the picture plate and the picture plate cutting means, as distinguished from means heretofore used in which the scanning and cutting were done by harmonic movement, and further to provide such an arrangement in which a pulsating current is used for producing a screen effect in the picture plate and also for synchronizing the movement between the picture and the scanning means with the movement between the picture plate and the picture plate cutting means.

Another object of the invention is to provide a half-tone picture transmitting current of such characteristics that it can be transmitted over wire circuits without the use of a carrier current and to eliminate the equipment heretofore used for transmitting half-tone picture currents by the aid of carrier currents,

Reference is hereby made to my copending applications Serial Number 645,384, filed December 2, 1932; Serial Number 647,884, filed December 19, 1932; which show details of a scanning head, screening systems, amplifier units and cutting heads with lifting mechanisms for the latter.

Other objects and advantages of the present invention will be apparent from the following specification which describes illustrative examples thereof and from the drawings forming a part of this application which illustrate somewhat diagrammatically the examples described, and from the appended claim hereof.

In the drawings:

Figure 1 is a plan view and diagram illustrating diagrammatically picture scanning and picture plate engraving machines and a system connecting them for picture transmission by a two channel wire circuit;

Figure 2 is a plan view showing somewhat diagrammatically a picture scanning and picture plate engraving machine of Figure 1;

Figure 3 is an elevation view in part section of Figure 2, taken along the line 3—3 of Figure 2, looking in the direction of the arrows;

Figure 4 is a plan view of a worm driven fly-wheel having a driving cam, shown in Figure 3;

Figure 5 is a section view diagrammatically showing a detail in Figures 2 and 3;

Figure 6 is a diagrammatic showing similar to that of Figure 1 but in which two channel radio transmission is used;

Figure 7 is a diagrammatic showing similar to that of Figures 1 and 6 but in which one channel, either wire or radio, is used for transmission; and

Figure 8 is a diagram of a single station equipped either to send or to receive in transmission by a single channel, either by wire or radio.

(1) TWO CHANNEL WIRE TRANSMISSION

(1) The sending station

Referring now to Figure 1 of the drawings, in which is illustrated somewhat diagrammatically a sending station 1 and a receiving station 2 connected by two pairs of wires, one for carrying the picture cutting current and the other pair for carrying the synchronizing current, a picture scanning and engraving machine 3 has a supporting bed 10 (see also Figures 2, 3 and 4) which carries at one end a pair of side rails 11, 11 having the aligned horizontal slats 12, 12, which support and guide for horizontal movement the picture scanning table 14 and at the

opposite end a pair of side rails 16, 16 having the aligned horizontal slots 17, 17 which support and guide for horizontal movement the plate cutting table 18. Means for moving said tables 14 and 18 synchronously in horizontal movement are provided comprising racks 20 and 21 fixed, respectively, to the bottoms of said tables 14 and 18, shafts 22 and 23, carried, respectively, by said pairs of side rails 11, 11 and 16, 16, which shafts 22, 23 carry the driving pinions 24 and 25, respectively, which latter engage said racks 20 and 21, respectively, in driving relation.

On its inner end, each of said shafts 22, 23 carries an adjustable double cone element 26 of a positive, infinitely variable driving unit 27 comprising also a link belt 28 and a second adjustable, double cone element 29. A shaft 30 (carried by bearings not shown, but generally included in said units 21, 21) carries both said elements 29, 29 and also a spiral herringbone pinion 31. Beneath said pinion 31 and in driving relation thereto, is the herringbone rack 32 which is fixed to a spline 33 which latter is moveable back and forth horizontally in a slot 35 in said bed 10. A pin 36, carried by said spline 33 and extending downwardly therefrom, engages a driving cam-slot 38 formed in a flywheel 40 mounted horizontally for rotation beneath said spline 33. Said cam-slot 38 is of a modified cardioid form shown in Figure 4 adapted by means of that portion thereof identified by the arc "C" to drive said rack 32 (and the parts driven thereby) at a constant rate of speed and by means of that portion thereof indicated by the arc "R" to return said rack 32 with harmonic motion in about one third of the driving time. It will be seen that for each complete revolution of said cam-slot 38 said tables 14 and 18 will each make a complete forward and return stroke. Said cam-slot 38 is smoothed off where sections "C" and "R" are joined so as to provide smooth change from one to the other.

Said flywheel 40 is driven by a constant speed shunt motor 42 (or other constant speed driving means) which also drives a single phase synchronous generator 44 mounted on the common drive shaft 45 which latter carries a worm 46 which in turn drives the gear 47 mounted about the periphery of said flywheel 40. The relation of said gear 47 to said worm 46 is accurately predetermined to be such that for each complete revolution of said cam slot 38 said shaft 45 is rotated an exactly complete multiple of revolutions, that is, without any fractional revolution. By these means said picture table 14 and plate table 18 are driven on a forward stroke (the scanning and cutting stroke) at a predetermined, constant speed and on a return stroke about three times as fast as the forward stroke (or other arrangement for any other predetermined relative speeds).

The positive, infinitely variable driving unit 27 mentioned above can be of the type described in "P. I. V. Gear, Book No. 1274," second edition, published April 1931, by Link-Belt Company, Chicago, Illinois, a copy of which will be found in the Patent Office.

Said flywheel 40 carries a shaft 50 which extends downwardly through a lower level 52 of said bed 10 below which said shaft 50 carries a bevel gear 53 which drives the two pinions 54 and 55, one on either side thereof, which latter drive respectively the shaft 56 and bevel gear 57 and shaft 58 and bevel gear 59, bearings not shown being provided for said shafts 56 and 58. In turn, said bevel gears 57 and 59 drive, respec-

tively, the pinion 61 and shaft 62 and pinion 63 and shaft 64. Said shafts 62 and 64 extend upwardly in close proximity, respectively, to the inner ones of said side rails 11, 11 and 16, 16 where they drive respective sets of change gears 67 and 68 which in turn through speed reducers 69 and 70 drive the pulleys 71 and 72, respectively.

Said pulley 71 drives an endless belt 73, which can be a tight wire, which at its opposite end passes over an idler pulley 74 which is mounted to the outer one of said side rails 11, 11. Said belt 73 is connected in operating relation to a scanning head 75 by a set screw 76. Said scanning head 75 rides on a horizontal bar 77 mounted over one strand of said belt 73 and supported by the posts 78, 78 which have openings 79, 79 for the passage of said belt 73 and which rest on said side rails 11, 11. Beneath said scanning head 75 is shown a picture 80 resting on said picture scanning table 14 and held thereon by suitable means not shown, such as a suction system. Extending lengthwise of said table 14 is a black marking strip 81 of appreciable width having a white marker 82 adjustable lengthwise thereon (or a white strip with a black marker) the purpose of which will be hereinafter fully described.

Said pulley 72 drives an endless belt 83, similar to belt 73, which at its opposite end passes over the idler pulley 84, mounted to the outer one of said side rails 16, 16. Said belt 83 is connected in operating relation to a cutting head 85 by a set screw 86. Said cutting head 85 rides on a horizontal bar 87 mounted over one strand of said belt 83 and supported by the posts 88, 88 which have openings 89, 89 for the passage of said belt 83 and which rest on said side rails 16, 16. Beneath said cutting head 85 is shown a picture receiving plate 90 resting on said plate cutting table 18 and held thereon by suitable means not shown, such as a magnetic chuck.

Said scanning head 75 and cutting head 85 are of the types shown and described in my co-pending applications identified above. Said scanning head 75 includes a photosensitive cell 45 not shown here and said cutting head 85 includes a cutting tool not shown here. Said shaft 50 at its lower end carries a short-circuiting commutator 91 having inset therein for part of its width an insulating segment 92 which extends through an angle equal to the arc "C" of said cam-slot 38. Said commutator 91 cooperates with the brushes 93, 93 which latter connect through a source of power 94 through the leads 95, 95 to means (not shown) within said cutting head 85 for lifting the cutting tool out of cutting position on the return stroke of the cutting table in a manner similar to that described in said co-pending applications.

A source of direct current is supplied through 60 mains 96, 96 and switch 97 to said motor 42. Leads 98, 98 connect from said mains 96, 96 through switch 99 to the field of said synchronous generator 44. Output leads 100, 100 from said synchronous generator 44 serve to connect 65 to mains reaching a synchronizing system at a distant station as hereinafter fully described.

Said shaft 50 also carries a scanning disc 101 which is in operative relation to interrupt a beam of light passing from a screening system 70 102 to a photosensitive cell 103. Said scanning disc 101 has a given number of light passages therein to secure a desired sized screening on the plate to be cut with said motor 44 running at a given speed, and when it is desired to transmit a 75

picture with a different sized screen without changing the speed of said motor 44 the disc can be replaced by another having the necessary number of light passages. However, the change in size of screen can be made by having a scanning disc with a multiplicity of annular rows of light passages, each row having a different number of light passages to suit a different sized screen, and having the said photosensitive cell 103 adjustably moveable to register with any desired row of light passages. Such an arrangement of scanning disc, screening system and photosensitive cell is described in the above identified copending applications, from which it will be seen that the function of said scanning disc 101 is to produce successive cutting engagements of the cutting tool in said cutting head 85 whereby there is produced a row of indentations on said picture plate 90 for each cutting stroke of said cutting table 18. And because said scanning disc 101 makes a certain number of complete revolutions for each complete revolution of said cam-slot 38 and for each complete forward and back movement of said table 18, the indentations (and also the intervening cameo reliefs) in the completed picture plate 90 will be arranged with their centers aligned in longitudinal and transverse rows which are substantially at right angles to each other.

It can be seen clearly from the above description and from the descriptions of the corresponding parts in said above identified copending applications that by adjusting said driving units 27, 27 said tables 14 and 18 can be arranged to move synchronously in complete forward and back movements for either one to one, or enlarging or reducing reproduction of the picture 80 on said table 14 onto said plate 90 on table 18. Likewise said gears 67 and 68 can be changed or adjusted to produce a corresponding transverse movement of said scanning head 75 and cutting head 85.

Referring again more particularly to Figure 1, said scanning head 75 connects through the pair of leads 105, 105 to the input side of an amplifier unit 106 fully described in said above identified copending applications. From the output side of said amplifier unit 106 a pair of leads 107, 107 connect to said screening system 102. From said photo-sensitive cell 103 a pair of leads 108, 108 connects to the input side of a voltage amplifier 110. Said unit 110 comprises one stage of resistance capacity coupled amplification and one stage of transformer coupled amplification, but any type of voltage amplifier can be used such as those well known in the art. From the output side of said unit 110 a pair of leads 111, 112 connect through a switch 114 to a parallel push-pull cutting amplifier unit 115. From the output side of said unit 115 the leads 116, 117 and 118 connect to said cutting head 85 which is of a push-pull type similar to that described in my said copending applications above identified.

From said lead 111 there extends a pair of leads 120, 121, one from each side of said switch 114, to one side of the double pole double throw switch 122. The other side of said switch 122 connects through leads 123, 123 to the telephone or other signalling transmitter 124 and source of power 125 which are in series with each other. The blades of said switch 122 connect to a pair of leads 130, 131, the former of which includes the primary of a line transformer 132 from the secondary of which there extends the pair of power mains 134, 134 which connect to the dis-

tant receiving station 2 in a manner hereinafter fully described. A set of single pole single throw switches 135, 135, 135 in series with each other serve to connect said lead 130 to said lead 131 when only the power mains 134, 134 are used; and other pairs of power mains 136, 136, 136, connect from each side of one of said switches 135, 135, 135, any or all of which are left open when receiving stations connected by any of said mains 136, 136, 136 are to be operated. By proper operation of said switches 122, 135, 135, 135, any or all of the receiving stations connected to the mains extending therefrom can be connected for operation by the sending station 1, and any number of receiving stations can be connected depending on the power supplied from said sending station 1 or other suitable arrangement. When a picture plate is to be produced at the sending station 1 without transmission to any distant station said switch 114 is closed and said switch 122 is opened. When a picture is to be transmitted to any distant station said switch 114 is opened and said switch 122 is connected to said leads 120 and 121. When a message or signal is to be sent to any distant station, such as for notification that a picture is about to be transmitted, said switch 122 is connected to said leads 123, 123 so that said transmitter 124 can be used, suitable corresponding receiving means being provided at the receiving station as hereinafter described.

Said leads 100, 100 from said synchronous generator 44 connect through the single pole double throw switch 140 through the leads 141, 142 the former of which includes the primary of a line transformer 144 from the secondary of which there extends the pair of power mains 145, 145 which connect to the distant station 2. A set of single pole single throw switches 146, 146, 146 in series with each other serve to connect said lead 141 to said lead 142 when only the power mains 145, 145 are used; and other pairs of power mains 147, 147, 147 connect from each side of one of said switches 146, 146, 146 any or all of which are left open when receiving stations connected by any of said mains 147, 147, 147 are to be operated.

(1) The receiving station

Still referring to Figure 1, at said receiving station 2 a picture scanning and engraving machine 150, having a bed 151, a scanning head 152, a cutting head 153, a picture receiving plate 154 and other parts somewhat similar to said machine 9 at said sending station 1 which latter are shown in detail in Figures 2, 3 and 4, is connected to the sending station 1 through said mains 134, 134 and 145, 145 through suitable apparatus as follows:

Said mains 134, 134 connect to the primary of the line transformer 158 the secondary of which connects through the leads 156, 156 to the input side of the voltage amplifier unit 157 which is similar to said voltage amplifier unit 110 at sending station 1. The output side of said voltage amplifier unit 157 connects through the leads 158, 158 and one side of the double pole double throw switch 159 to the input side of a parallel push-pull cutting amplifier unit 160 which can be similar to said push-pull cutting amplifier unit 115. The output side of said push-pull amplifier unit 160 connects through the leads 161, 162, and 163 to said cutting head 153.

The other side of said double pole double throw switch 159 connects to the loud speaker 164 or

other signal receiving means corresponding to said transmitter 124 of said sending station 1.

Said mains 145, 145 connect to the primary of a line transformer 165 from the secondary of which the leads 166, 166 connect to the input side of a voltage amplifier unit 167 which is similar to said voltage amplifier units 110 and 151. The output side of said voltage amplifier unit 167 connects through the leads 168, 168 to the input side of the parallel push-pull amplifier unit 169 similar to said amplifier units 115 and 160 with the exception that said amplifier unit 169 includes in its output side a transformer 170 the secondary of which connects through leads 171, 171 and switch 172 to the armature of a synchronous motor 174 which latter in said machine 150 takes the place of said synchronous generator 44 in said machine 9 at said sending station 1. Direct current mains 175, 175, having a switch 176 therein, connect through the leads 177, 177 having a switch 178 therein to the field of said synchronous motor 174. Said power means 175, 175 connect, through leads 179, 179 to a direct current shunt motor 180 in series with the field of which is provided a rheostat 181. Said rheostat 181 is used for starting and controlling the speed of said motor 180.

Said machine 150 is like said machine 9 of sending station 1 with the following exceptions.

(1) The substitution of said synchronous motor 174 for said synchronous generator 44. Arrangements can be made for using the generator as a motor and vice-versa in which case the sending station can be converted into a receiving station and the receiving station into a sending station, corresponding changes being made in the line and amplifier connections.

(2) The use of a synchronous motor at both the sending and receiving station machines 9 and 150 for synchronizing purposes. This arrangement can be used where the sending and receiving stations 1 and 2 are in places which have a common alternating current supply such as is the case in the present day where distant areas are interconnected by far reaching networks which tie in a number of power stations; in which case a synchronous motor in both the sending and receiving machines can be used because they will be kept in phase through the constant checking up of current conditions in the entire network which is common practice today. In such case the mains 145, 145 and 147, 147 and the amplifier units 167 and 169 can be eliminated and the direct current motors 42 and 180 can both be used as starting motors as above described for machine 150.

(3) The third difference between said machine 150 and said machine 9 (see Figure 5) is that the former has in series in one of said leads 95, 95 of said cutting head 85 a sound signalling device 182 comprising an electro-magnet 183 which is adapted to draw to it a bell hammer 184 having a tension spring 185 connected thereto and adapted to draw said bell hammer 184 against a bell gong 186. A single pole single throw switch 187 is adapted to short circuit said electromagnet 183. The purpose of this signalling device is to aid in getting the two machines into synchronism before transmission of a picture is actually begun.

Except as otherwise noted the parts of said machine 150 are numbered the same as corresponding parts of said machine 9 so that reference can be made to Figures 2, 3, 4 and 5 for details. In a general system all the machines such

as machines 9 and 150 can be alike, with the necessary amplifying units, switching arrangements and other parts selected from machines 9 and 150 to make each station fully equipped for either sending or receiving, at will. In each case, at the receiving machine as in the illustrative example shown in Figure 1, the scanning head and scanning disc are idle and the scanning table is running idle during the picture transmission operation.

(1) Operation of two channel wire system

When it is desired to make a picture plate at said receiving station 2 from a picture at said sending station 1 the operator there places a picture 80 on the picture table 14 and a picture plate 90 on the table 18 of machine 9, the length of stroke of the tables and the speed of transverse movement of scanning head 75 and cutting head 85 being properly adjusted to suit the ratio of reproduction. Said picture plate 90 can be cut whether it is to be used for printing or not because it can serve to show the sending operator the progress of the transmitting operation. The details of the necessary arrangements are to be transmitted from the sending station to the receiving station or stations by means of said telephone transmitter 124 and the loud speaker 164. He then loosens said set screws 76 and 86 and moves said scanning head 75 over said strip 81, the marker 82 of which is now adjusted to a position aligned with the beginning of the scanning stroke of said table 14, and said cutting head 85 into position to start the cutting of his plate. The energizing circuits of said units 106, 110 and 115 are now closed and the operator checks over his apparatus to see that it is in proper working condition. He then brings said motor 42 up to a predetermined operating speed. Said switch 122 is now connected to said leads 123, 123 in order to transmit verbal instructions from said telephone transmitter 124 to said loud speaker 164, the switch 159 of which latter is always left closed to it during such times as picture transmission is to be expected. The sending operator speaks a calling or warning signal into said transmitter 124 and follows with a statement that a picture is to be transmitted of such and such a nature, describing the subject of the picture; that the picture is of a given size; and that on his own machine he will cut a certain sized picture of a certain sized screen. He can also say that he will commence transmitting the picture at the end of a definite interval of time for example at the end of two minutes.

Said table 14 is now reciprocating and said black strip 81 and white marker 82 are being scanned by said scanning head 75. The sending operator now changes said switch 122 to connect it with said leads 120 and 121, opens said switch 114 and closes said switch 140. From said synchronous generator 44 a pulsating current is passing through said mains 145, 145 to the primary of said line transformer 165 of said receiving station 2. Also, through said mains 134, 134 a signal is being transmitted to said loud speaker 164 through the scanning of said black strip 81 and white marker 82, which signal is a loud sound at the beginning of each scanning stroke of said table 14.

Meanwhile the operator at said receiving station 2 energizes the circuits of said amplifier units 160, 167 and 169; loosens said set screw 86 of said cutting head 153 and moves the latter to

a position to start the cutting of his plate, 154; opens said switch 187; and closes said switch 176 to energize said motor 180 and set his machine into motion. If necessary, he now adjusts 5 said rheostat 181 to bring said motor 180 to such a speed that the signal produced by said sound signalling device 182 coincides in time with the signal produced by said loud speaker 164. This indicates that said machine 150 is in 10 synchronization with said machine 9. When this is accomplished the receiving operator closes said switch 178 and said switch 172 to energize the field and armature of said synchronous motor 174 which maintains synchronization between said 15 machines 150 and 9, and said machine 150 is ready to commence the cutting of a picture. As said signalling device 182 is no longer needed, said switch 187 is closed. Also said synchronous motor 174 can be strong enough to drive said 20 machine 150 in which case said motor 180 is cut off after being used to bring synchronous motor 174 up to speed.

At the end of the interval of time previously announced the sending operator moves said 25 scanning head 75 into position to commence scanning the picture, locking it therein by tightening said set screw 76 to start transverse movement and locking said set screw 86 to start corresponding movement of said cutting head 85. 30 When the sending operator moves said scanning head 75 from said black strip 81 and white marker 82 the signals produced by the latter at said loud speaker 164 will cease whereupon the receiving operator changes said switch 159 to 35 connect it to said amplifier unit 160 and tightens said set screw 86 to start said cutting head 153 in transverse movement.

Both machines are now in full operation and both are cutting picture plates. If receiving stations other than receiving station 2 are connected to said pairs of power mains 136, 136, 136 and 40 147, 147, 147 said switches 135, 135, 135 and 146, 146, 146 will be open and the same preparations will be made there as at said station 2, 45 otherwise switches 135, 135, 135 and 146, 146, 146 will be closed.

(2) Two CHANNEL RADIO TRANSMISSION

(2) The sending station

50 Referring now to Figure 6 of the drawings, in which is illustrated diagrammatically a two channel radio transmission system including a sending station 201 and a receiving station 202 said sending station 201 has all the essential parts of said sending station 1 of Figure 1 including a picture scanning and engraving machine 203, the amplifying unit 206 which has its input side connected to the scanning head 207, and its output side connected to the screening system 208; the voltage amplifier 210 having its input side connected to the photo sensitive cell 211; and the parallel push-pull cutting amplifier unit 212 having its input side connected to said voltage amplifier unit 210 through the leads 213, 213 one of which has a single pole single throw switch 214 therein and its output side connected to a cutting head 216. Said machine 203, like said machine 9, has also a scanning table 217, a cutting table 218, a scanning disc 219, a direct current driving motor 220, and a synchronous generator 221. Direct current power mains 222, 222 having the switch 223 therein, supply power to said direct current motor 220 and through the leads 224, 224 having a switch 225 therein, supply

the field current to said synchronous generator 221. Said scanning table 217 has a black strip 230 thereon having an adjustable white marker 231, similar to said strip 81 and marker 82 on said scanning table 14 of said machine 9 in Figure 1. A picture 232 is placed on said scanning table 217 when it is desired to reproduce the same, and a picture receiving plate 233 is placed on said cutting table 218.

10 In addition to these parts said sending station 201 has equipment for the radio transmission of the picture cutting current and the synchronizing current, as follows.

An alternating current generator in the form of an electron tube oscillator unit 234 has its 15 output side connected through the high frequency input leads 235, 235 to a radio transmitter in the form of the modulator unit 237 which has its output side connected to the ground 238 and the transmitting antenna 239. Such a combination 20 of oscillator and modulator is shown and described in "Telephone Communication" by Wright and Puchstein, McGraw-Hill Book Company, 1925, but various other systems of oscillator and modulator can be used. The low frequency input 25 side of said modulator unit 237 is connected to a double pole double throw switch 240, one side of which is connected to the leads 241, 241 which are across said single throw switch 214. The other side of said double pole double throw switch 240 is 30 connected across the telephone or other signalling transmitter 242. The leads 245, 245, including the switch 246, connect from the output side of said synchronous generator 221 to the low frequency input side of a radio transmitter unit 247 35 which has its output side connected to the ground 248 and transmitting antenna 249 and whose high frequency carrier current is supplied by the electron tube oscillator unit 250. Said radio transmitter unit 247 is similar to said modulator unit 237 and said oscillator unit 250 is similar to said oscillator unit 234.

(2) The receiving station

Said receiving station 202 has parts similar to 45 said receiving station 2 of Figure 1, as follows. A picture scanning and engraving machine 251 has its cutting head 252 connected to the output side of a parallel push-pull cutting amplifier 253 which latter has its input side connected to the 50 output side of the voltage amplifier unit 254 through one side of the double pole double throw switch 255 the other side of which latter is connected to the loud speaker 256. The leads 260, 260, having the switch 261 therein, connect from 55 the armature of the synchronous motor 262 to the output side of a parallel push-pull amplifier unit 263, the input side of which latter is connected to the output side of the voltage amplifier unit 264. Direct current mains 265, 265, having 60 a switch 266 therein, connect to the driving motor 267 having a rheostat 268 connected in series with the field thereof. Leads 269, 269, having a switch 270 therein connect said mains 265, 265 to the field of said synchronous motor 262. A 65 picture receiving plate 275 is positioned on the cutting table 276 beneath said cutting head 252. One of the leads 277, 277 to the lifting mechanism (not shown) of said cutting head 252 includes the single pole switch 278 across which is connected 70 the sound signalling device 279 which latter is similar to said sound signalling device 182 shown in Figures 1 and 5.

The input side of said voltage amplifier unit 254 is connected to the output side of a radio re- 75

ceiving unit 280 which has connected to its input side the ground 281 and the receiving antenna 282. Said radio receiving unit 280 is of a well known type and has a variable condenser 283 in its antenna ground system and another variable condenser 284 for tuning purposes. Other suitable forms of radio receiving units can be used. Similarly, the input side of said voltage amplifier unit 264 is connected to the output side of a radio receiving unit 285 having the variable condensers 286, 287 for tuning, a ground 288, and a receiving antenna 289.

15 (2) *Operation of two channel radio transmission system*

When the operator at said sending station 201 has a picture to be transmitted to said receiving station 202 he goes through substantially the same preparatory operations and steps as are described above for the system illustrated in Figure 1. The warning signals and messages from said transmitter 242 to said loud speaker 256 are of course sent by radio in this system, and said radio receiving unit 280 and voltage amplifier unit 258 are kept tuned in to receive messages from said radio transmitter unit 237 and said switch 255 is kept closed to said loud speaker 256 at such times as picture transmission can be expected. Also said radio receiving unit 285 is kept tuned in to receive signals from said radio transmitting unit 247.

After the necessary instructions have been sent from said sending station 201 and the sending station is in readiness for transmission, the above described synchronizing operations are carried on and completed the picture reproducing current and the synchronizing current are combined with their respective carrier waves and transmitted to the receiving station 202. The transmission of a picture from said sending station 201 to said receiving station 202 is substantially the same as described for the sending and receiving stations of Figure 1.

45 (3) *ONE CHANNEL, EITHER WIRE OR RADIO TRANSMISSION*

(3) *The sending station*

Referring now to Figure 7 of the drawings, there is illustrated diagrammatically a single channel system adapted for either wire or radio transmission and including a sending station 301 and a receiving station 302. In this system, with either wire or radio transmission, the picture cutting current is used also for synchronizing the receiving station 302 with said sending station 301, as hereinafter fully explained.

Similar to the systems illustrated in Figures 1 and 6, the system of Figure 7 has a picture scanning and engraving machine 310 having a picture scanning table 311 which has thereon a black strip 312 with an adjustable white marker 313, a plate cutting table 314, a scanning head 315 over said scanning table 311, a cutting head 316 over said cutting table 314, a scanning disc 317, and a constant speed shunt wound motor 318 having a rheostat 319 in series with the field thereof. Said shunt wound motor 318 drives said scanning table 311, said cutting table 314 and said scanning disc 317 in a manner as disclosed above in the description of the machine of Figures 2 to 4. For some purposes a synchronous motor 320 mounted on the shaft of said shunt motor 318 and scanning disc 317 is used as hereinafter described. The direct current mains

321, 321, having the switch 322 therein, supply current to said shunt motor 318, with leads 323, 323 having a switch 324 therein for connecting said synchronous motor 320 to said mains 321, 321 when desired. When it is desired to use said machine 310 a picture 325 is placed on said scanning table 311 and a picture receiving plate 326 is placed on said plate cutting table 314.

On one side of said scanning disc 317 is mounted a screening system 330 and in operative relation on the other side of said scanning disc 317 is mounted a photosensitive cell 331. An amplifier unit 332 has its input side connected to said scanning head 315 and its output side connected to said screening system 330. A voltage amplifier 333 has its input side connected to said photosensitive cell 331 and its output side connected through a single pole single throw switch 334 to the input side of a parallel push-pull cutting amplifier unit 335, the output side of which latter is connected to said cutting head 316.

Across said switch 334 is connected the double pole double throw switch 336 from one side of which latter extend the leads 340 and 341, which latter has in series therein the single pole single throw switches 342, 342, 342 each of which latter has connected thereacross a pair of power mains 343, 343, 343. A line transformer 344 has its primary connected to said leads 340 and 341 and its secondary connected to the power mains 345, 345.

The other side of said switch 336 connects through the leads 347, 347 to the low frequency input side of the radio transmitter 348 which latter has its high frequency input side connected to the oscillator unit 349 and its output side connected to the transmitting antenna 350 and the ground 351.

Across said leads 347, 347 is connected one side of a double pole double throw switch 352 which latter has connected thereto the telephone transmitter 353, and which has its other side across said leads 340 and 341.

(3) *The receiving station*

At said receiving station 302 is a picture scanning and engraving machine 354 similar to said machine 310 at said sending station 301 and which has a plate cutting table 355 which carries a plate 356 and over which is a cutting head 357. One of the leads 358, 358 to the lifting mechanism (not shown) of said cutting head 357 includes the single pole switch 359 across which is connected the sound signalling device 360 which latter is similar to said sound signalling device 182 shown in Figures 1 and 5 and device 279 shown in Figure 6.

The constant speed shunt motor 361 of said machine 354 has a rheostat 362 in series with the field thereof and is fed by the power mains 363, 363 having the switch 364 therein. On the shaft 365 of said shunt motor 361 is the synchronous motor 366 which is connected to said power mains 363, 363 by the leads 367, 367 having the switch 368 therein. Said shaft 365 can also carry a scanning disc 369.

The armature of said synchronous motor 366 is connected through the switch 370 to the output side of a parallel push-pull amplifier unit 371 the input side of which is connected in series with the input side of the parallel push-pull cutting amplifier unit 372 the output side of which latter connects to said cutting head 357. A double pole double throw switch 373 connects on one side to the input sides (in series) of said push-pull

amplifiers 371 and 372 and on its other side to the loud speaker 374. The blades of said switch 373 connect to the output side of the voltage amplifier unit 375 the input side of which latter connects to the double pole double throw switch 376, which latter connects on one side to the output side of the radio receiving unit 377 which has connected to its input side the ground 378 and the receiving antenna 379. A variable condenser 380 in the antenna ground system and another variable condenser 381 in the main circuit of said radio receiving unit 377 serve to tune said receiving station 302 to said sending station 301 or to any other suitable sending station.

15 The other side of said switch 376 connects to the secondary of a line transformer 382 the primary of which connects to said power mains 345, 345 from said sending station 301.

20 (3) *Operation of one channel, either wire or radio transmission*

When a picture is to be transmitted from said sending station 301 to said receiving station 302 of Figure 7 by wire, the preliminary warning and verbal communication is made possible by closing said switch 352 to said leads 340 and 341 (said switches 342, 342, 342 being closed when there are no receiving stations connected to said power mains 343, 343, 343). When wire transmission is to be expected at said receiving station 302 said switch 376 is closed to said line transformer 381 and said switch 373 is closed to said loud speaker 374. A warning and verbal instructions having been communicated from said transmitter 353 to said loud speaker 374, said switches 334 and 352 are opened and said shunt motor 318 having been brought up to a predetermined standard speed, the sending operator sends synchronizing signals by means of said strip 312 and marker 313. The receiving operator opens the switch 359 of said sound signaling device 360, starts said motor 361 and, by means of said rheostat 362, synchronizes his machine with that at the sending station by regulation in accordance with signals produced by said sound signalling device 360 and said loud speaker 374 in a manner described in connection with the operation of the system of Figure 1. At the end of an interval of time the sending operator moves said scanning head 315 into scanning position and locks it for transverse movement, as a result of which the synchronizing signals from said loud speaker 374 cease whereupon the receiving operator changes said switch 373 to connect it to said push-pull amplifier units 371 and 372, closes said switches 359 and 368 and switch 370 and locks his cutting head for transverse movement. Said machine 354 is now operating with the movement of said picture plate 356 (through said motors 361 and 366) and the operation of said cutting head 357 in synchronism with the movement of said picture 325. This synchronization is produced through the regulation of the speed of said shunt motor 361 by said synchronous motor 366 which receives regulating current impulses from said amplifier unit 371 simultaneously with the passage of operating current impulses from said amplifier unit 372 to said cutting head 357.

70 When the system of Figure 7 is to be used with radio transmission the preparations are the same as those above described for wire transmission except that the various switches are operated to cut in the radio transmitting and receiving units instead of those for the wire system,

as follows. When the sending operator is to use said telephone transmitter 353 he closes said switch 352 to said leads 341, 341, and likewise when the receiving operator expects transmission by radio he closes said switch 376 to the output side of said radio receiving unit 377. After the verbal instructions have been given said switches 334 and 352 are opened and said switch 336 is closed to said leads 341, 341, at the sending station. After the necessary synchronizing signals have been sent said switch 359 is closed and said switch 373 is changed from said loud speaker 374 to connect onto said push-pull amplifier units 371 and 372 at the receiving station. The operators then having locked the scanning head 315 and cutting heads 316 and 357 in position for transverse movement, the transmission of the picture commences.

The pulsating currents from said amplifier units 371 and 372, although not in the usual sinusoidal form employed for operating synchronous motors, are of constant frequency and while each cut is being made in said plate 356 by a given impulse from said amplifier unit 372, the speed of said motor 361 and thereby movement of said plate 356 are being differentially regulated by a simultaneous current impulse passing through said synchronous motor 366. This system insures accurate synchronization between the speed and operation of the sending machine and the receiving machine, and, once the system has been set in engraving operation, any variation or change in the speed of the sending machine will result in a simultaneous and corresponding change in the receiving machine.

It is to be understood that other means equivalent to said synchronous motor 366, either old and well known such as a phonic motor or new means, can be used in place thereof for utilizing the current pulsations delivered by said push-pull amplifier 371 for the purpose of keeping said shunt motor 361, and the parts driven thereby, synchronized with said machine 310 of said sending station 301. Also, when desired or required, means can be used for receiving the current from said push-pull amplifier unit 371 to change the characteristics of said current and deliver to said synchronous motor 366 a sinusoidal current whose value varies in accordance with that of said current delivered by said unit 371, and consequently in accordance with variations in characteristics of current passing through said photoelectric cell 331.

55 (4) *STATION EQUIPPED TO TRANSMIT OR RECEIVE BY WIRE OR RADIO, FOR ONE CHANNEL SYSTEM*

(4) *Wire transmission*

Referring now to Figure 8 of the drawings there is shown therein somewhat diagrammatically a station 400 which has all the equipment necessary for sending or receiving either by wire or radio, in the transmission of a picture to be cut into a screen half-tone printing plate.

In the following description reference is made to Figure 7 of the drawings.

First, said station 400 will be described as a station for sending by wire. Such a station comprises a picture scanning and engraving machine 401 whose scanning head 402 is connected to the input side of the amplifier unit 403 which latter has its output side connected by the leads 404, 404, having a switch 405 therein, to the screening system 406. A pair of power mains 407, 407 hav-

ing a switch 409 therein, connect to the shunt motor 409 and have tapped therefrom a pair of leads 410, 410 which connect through a switch 411 to a synchronous motor 412 (not used when sending) on a common shaft 413 with said shunt motor 409 and a scanning disc 414.

A photosensitive cell 415, in operative relation with said screening system 406 and said scanning disc 414, connects by leads 416, 416 through a switch 417 and leads 418, 418 to the input side of the voltage amplifier unit 419, from the output side of which latter extend the leads 420 and 421. Said lead 421 connects to a lead 422 to one blade of a double pole double throw switch 423, from the other blade of which latter a lead 424 connects through a lead 425 to one blade of a double pole double throw switch 426, the other blade of which latter connects to said lead 420. In one closed position said double pole double throw switch 423 connects through a pair of leads 427, 427, including the series connected single pole switches 428, 428, 428, to the primary of the line transformer 429, the secondary of which connects to the power mains 430, 430. Additional pairs of power mains 431, 431, 431 are tapped across said switches 423, 428, 428. A pair of leads 432, 432 connect from across said leads 427, 427 to one side of a double pole double throw switch 433 whose blades connect to the telephone transmitter 434 and source of power 435 therefor.

Said double pole double throw switch 426 in one closed position connects through the leads 436, 436 to the input side of the parallel push-pull cutting amplifier unit 437 whose output side connects to the cutting head 438 of said picture scanning and engraving machine 401. Leads 439, 439 from a lifting device (not shown) in said cutting head 438 connect to a lifting device energizing means, not shown but fully described together with the lifting device in the description of Figures 1 to 5 of the drawings. One of said leads 439 has therein a single pole single throw switch 440 across which is connected the sound signalling device 441. Said amplifier unit 403, voltage amplifier unit 419 and cutting amplifier unit 437 correspond respectively to said amplifier unit 332, voltage amplifier unit 333 and cutting amplifier unit 335 of Figure 7.

(4) Radio transmission

For transmission by radio said double pole double throw switch 423 connects in its other closed position through a pair of leads 445, 445 to the low frequency input side of the radio transmitter 446 the high frequency input side of which latter connects to the oscillator unit 447. From the other side of said double pole double throw switch 423 a pair of leads 448, 448 connect across said leads 445, 445. Said radio transmitter unit 446 and oscillator unit 447 correspond respectively to said radio transmitter 349 and oscillator unit 349 of Figure 7.

(4) Wire reception

For reception by wire said leads 427, 427 connect through the pair of leads 450, 450 to one side of the double pole double throw switch 451 whose blades connect to the pair of leads 452, 452 which connect to one side of said double pole double throw switch 417 opposite to said leads 416, 416. Said lead 421 connects to a lead 453 to one blade of a double pole double throw switch 454, across one side of the latter through the bus bar 455, through the other blade of said switch 454, and through lead 456 to said lead 425. In its other

closed position said switch 426 connects through the leads 457, 457 to the loud speaker 458. The other side of said switch 454 connects through the leads 459, 459 to the input side of the parallel push-pull amplifier unit 460 whose output side 5 connects through the leads 461, 461 to the armature of said synchronous motor 412. Said amplifier unit 460 corresponds to said amplifier unit 371 of Figure 7.

(4) Radio reception

10

The other side of said double pole double throw switch 451 connects through the leads 462, 462 to the output side of the radio receiving unit 463, which latter corresponds to said radio receiving unit 371 of Figure 7.

(4) Operation

When sending by wire, all of the switches being open, the sending operator closes said switch 433 to said leads 432, 432 to communicate verbal instructions, said switches 428, 428, 428 being closed if only a receiving station connected to said power mains 430, 430 is to be used. After verbal instructions have been sent said switch 433 is opened; said switch 408 is closed; said switch 440 is closed; said double pole single throw switch 405 is closed; said switch 417 is closed to said leads 416, 416; said switch 426 is closed to said leads 436, 436; and said switch 423 is closed to said leads 427, 427, for sending synchronizing signals and for transmitting the picture.

When sending by radio, the switching operations are the same as for sending by wire except that said switch 433 is closed to said leads 448, 35 448 (for communication of verbal instructions), and said switch 423 is closed to said leads 445, 445.

When reception is expected by wire, through said power mains 430, 430, said switches 428, 428, 40 428 being closed and all others opened; said switch 451 is closed to said leads 450, 450; said switch 417 is closed to said leads 452, 452; said switch 454 is closed to said bus bar 455; and said switch 426 is closed through said leads 457, 457 to said loud speaker 458. After verbal instructions have been received through said loud speaker 458 said switch 408 is closed and said machine 401 is brought into synchronism with the transmitting station as above described for the operation of Figure 1. 50 After said machine 401 is synchronized and the synchronizing signals cease, said switch 411 is closed; said switch 426 is changed to said leads 436, 436; said switch 458 is changed from said bus bar 455 to said leads 459, 459 and said switch 440 is closed, and said machine 401 is ready to start cutting a picture plate.

For receiving by radio the switching operations are the same as for receiving by wire except said switch 451 is closed to said leads 462, 462 instead of said leads 450, 450.

In the above description and in the drawings well known forms of amplifier units have been shown and certain connecting and switching arrangements have been disclosed but many other 65 variations and combinations can be used when desired or required, such for example as to suit power and transmission requirements.

Having thus described my invention what I claim and wish to protect by Letters Patent is— 70

In a system for producing a picture printing plate at a distance from a scanned picture, in combination, a sending station having a picture carrier, scanning means, means for producing relative reciprocating movement between the two 75

latter with a constant speed scanning stroke and a quick return stroke, said scanning means including a photo-electric means in operative relation to scan a picture on said picture carrier and adapted to transmit a current having an inherent maximum value varying in accordance with variations in tones of a scanned picture, and means including a second photo-electric cell, a light source therefor and an interrupter therebetween for producing a second regularly timed pulsating current varying in amplitude in proportion to the amplitude of first said current; and a receiving station having a picture plate carrier, an electric cutting head adapted to operate in plate cutting vibrations, and means for producing relative reciprocating movement between the two latter with a constant speed cutting stroke and a quick return stroke including a synchronous motor, said electric cutting head adapted to be controlled by said regular timed pulsating cur-

rent from said sending station to produce cutting vibrations, one vibration for each impulse, and to be controlled by said regular timed pulsating current in accordance with the variations in amplitude thereof to control the strength of said vibrations, said synchronous motor controlled by said regular timed current pulsations to maintain accurately constant speed of said reciprocating movement synchronous with the reciprocating movement in said sending station, both during the cutting stroke and during the return stroke of said relative reciprocating movement, and means for rendering said electric cutting head inoperative with respect to a plate on said picture plate carrier during the return stroke of said relative reciprocating movement and to return said electric cutting head to the cutting relation during the cutting stroke.

GEORGE E. LOSIER. 20
